RAILWAY TRAFFIC CONTROLLING
APPARATUS

Paul H. Crago, Wilkinsburg, Pa., assignor to The
Union Switch & Signal Company, Swissvale,
Pa., a corporation of Pennsylvania

Application August 19, 1936, Serial No. 96,833

12 Claims. (Cl. 246—63)

My invention relates to railway traffic controlling apparatus, and particularly to apparatus operative to effect a warning cab signal indication upon approach to a permanent track hazard.

5 I will describe two forms of the apparatus embodying my invention, and will then point out the novel features thereof in claims.

In the accompanying drawings, Fig. 1 is a diagrammatic view of one form of apparatus embodying my invention, and Fig. 2 is a diagrammatic view of a second form of apparatus which also embodies the invention. Fig. 3 is a diagram illustrating an operating characteristic of the apparatus of Figs. 1 and 2.

13 In each of the different views, like reference characters designate similar parts.

Referring to Fig. 1, a stretch of railway track over which traffic normally moves in the direction indicated by an arrow is formed by the usual insulated rail joints into successive track sections, only the adjacent ends of two sections 1T and 2T being shown in the drawings for the sake of simplicity. That is, only one signal location A is shown in Fig. 1 and it will be understood that each junction of adjacent sections constitutes a signal location similar to location A. This stretch of railway is provided with a track-way apparatus necessary for a combined wayside and cab signal system, the cab signal system being of the code type. The apparatus for this combined wayside and cab signal system is preferably that in general use and will be described in the present application only insofar as is necessary for a full understanding of my invention.

35 As here shown, the apparatus is that necessary to effectively operate a cab signal capable of displaying clear, approach, slow, and stop indications; and to effectively operate a wayside signal capable of displaying clear, approach, and stop indications. The train carried equipment for a cab signal system of the type here contemplated may be that disclosed and claimed in the United States Letters Patent No. 1,773,472, granted August 19, 1930, to P. N. Bossart, for Railway traffic 40 controlling apparatus, and to which patent reference may be made for a full understanding of such train carried cab signal equipment. The wayside signals may be any one of the standard three-position signals such as, for example, position light signals. The wayside signal S at location A is shown conventionally only for the sake of simplicity since the structure of the signal and the operating circuits therefor form no part of the invention, and are well known.

55 Each track section of the system is provided

with a track circuit consisting of a source of current connected across the rails at the exit end of the section and a track relay connected across the rails at the entrance of the section. Hence, the source of current for the track circuit of section 1T and the track relay for the track circuit of section 2T are located at the signal location A. The immediate source of current for the track circuit of section 1T is the secondary winding 2 of a track transformer T1, the primary 10 winding 3 of which is at times supplied with non-coded alternating current and at other times with coded alternating current as will appear herein-after.

15 In a combined wayside and cab signal system 15 of the type here involved two independent sources of alternating current are commonly provided. As here shown, the secondary winding 7 of a line transformer TL1 is a source of 60 cycle alternating current by virtue of the primary winding 8 20 of that transformer being connected with a 60 cycle alternating current generator not shown. The secondary winding 9 of a line transformer TL2 is a source of 100 cycle alternating current by virtue of the primary winding 10 of transformer TL2 being connected with a 100 cycle 25 alternating current generator not shown. The secondary winding 7 of line transformer TL1 is connected across two bus bars BX and CX, and one terminal of secondary winding 9 of transformer TL2 is connected directly with bus bar CX over wire 42 and its other terminal is connected with a circuit network to be described later. The 60 cycle alternating current is used for energizing the track circuit under normal conditions, that is, when the track section is unoccupied, and to operate the wayside signal system. The 100 cycle alternating current is coded and is used to influence the train carried cab signal 30 equipment in the manner described in the aforementioned Bossart patent. One terminal of primary winding 3 of track transformer T1 is connected over wire 12 with the CX bus bar and the other terminal of winding 3 is connected with bus bar BX over wire 13, front contact 14 of a 35 relay 2V to be referred to later, and wire 15. It follows that at such time as relay 2V is energized and its front contact 14 is closed, non-coded 40 60 cycle alternating current is supplied to the track rails of section 1T, but that entry of a 45 train into section 1T to shunt the track relay of that section and cause the relay 2V to be de-energized in a manner to shortly appear, the supply of 60 cycle alternating current to the rails of section 1T is discontinued. The code selection 50 55

circuit network by which secondary winding 9 of line transformer TL2 is at times connected with the primary winding 3 of track transformer T1 for supplying coded alternating current to the 5 rails of section 1T will be described later. It will be understood, of course, that alternating current of a single frequency may be used for both the wayside and cab signal equipments.

The track relay 2TR for the track circuit of 10 section 2T is a two element alternating current relay responsive to 60 cycle alternating current. An approach relay 2V and a line relay 2SA are provided at location A. Relay 2V is governed over a line circuit including line wire 4 extending 15 to the location in the rear of location A and at which rear location it is connected to the 60 cycle alternating current source in the same manner that line wire 5 leading to the V relay at the location in advance of location A is connected over 20 front contact 6 of track relay 2TR with the 60 cycle alternating current source at location A. Thus, relay 2V is normally energized by current supplied from the location in the rear of location A and is deenergized in response to a train entering 25 section 1T and shunting the track relay of that section. The line relay 2SA is governed over a line circuit (not shown) responsive to traffic conditions in advance of section 2T. This line circuit would be in accordance with standard 30 practice. Consequently, under clear traffic conditions in advance of location A and which permits high train speeds through section 2T, both track relay 2TR and line relay 2SA are picked up; under approach traffic conditions that require a speed 35 restriction, track relay 2TR is picked up and line relay 2SA is down; and when section 2T is occupied, track relay 2TR is released.

The apparatus at location A also includes a code transmitter CT. The type of code transmitter is 40 immaterial, and, as here shown, the operating winding 16 thereof is supplied with current from any convenient source, such as the BX-CX bus bars, over a simple circuit including back contact 45 17 of relay 2V. The code transmitter CT operates three coding contact members 80, 120, and 180 the arrangement being such that coding contact member 80 is operated between two stationary contacts 18 and 19 at the rate of 80 times per minute, contact member 120 is operated between 50 two stationary contacts 20 and 21 at the rate of 120 times per minute, and contact member 180 is operated between two stationary contacts 22 and 23 at the rate of 180 times per minute. It follows that the code transmitter CT is normally 55 inactive and is energized and rendered active to operate its code contact members in response to a train entering section 1T and shunting the track relay of that section to cause relay 2V to be deenergized. As pointed out hereinbefore, the 60 supply of non-coded 60 cycle alternating current is removed from the primary winding 3 of track transformer T1 when relay 2V is released and its front contact 14 is opened. In the event of clear traffic conditions in advance of location A and 65 relays 2TR and 2SA are both picked up when relay 2V is released, 100 cycle alternating current coded at the 180 code is supplied to primary winding 3, and hence is supplied to the track rails of section 1T where it is effective to establish a clear 70 cab signal indication for the train carried equipment of the train the entry of which into section 1T causes the release of relay 2V. This 180 code selection circuit may be traced from the right-hand terminal of primary winding 9 over back 75 contact 35 of relay 2V, wire 36, contact 22, code

contact member 180, wire 37, a circuit network to be later described in detail to wire 38, thence over front contacts 39 and 40 of relays 2SA and 2TR, respectively, wires 41 and 13, primary winding 3 of track transformer T1, wire 12 to bus bar CX, and wire 42 to the left-hand terminal of primary winding 9. In the event of approach traffic conditions in advance of location A and relay 2TR is picked up and relay 2SA is released when relay 2V is deenergized, 100 cycle alternating current of the 120 code is supplied to the primary winding 3 of track transformer T1 to effect the approach indication of the cab signal. The 120 code selection circuit includes secondary winding 9, back contact 35 of relay 2V, wire 36, contact 20, code contact member 120, wires 43 and 44, back contact 45 of relay 2SA, front contact 40 of track relay 2TR, and thence as previously traced for the 180 code selection circuit. Again, if the section 2T is occupied and track relay 2TR is down when the relay 2V is released, 100 cycle alternating current coded at the 80 code is supplied to the primary winding 3 of track transformer T1 to effect the display of a slow cab signal. The 80 code selection circuit extends from secondary winding 9 over back contact 35, wire 36, contact 18, code contact member 80, wire 46, back contact 47 of relay 2TR, and thence as previously traced. In the case the track section 2T is occupied by a preceding train and rail current is shunted by the wheels and axles of the preceding train the cab signal equipment of a following train entering section 2T is deenergized to effect the display of the stop cab signal. It is to be noted that by means of the contacts 19, 21, and 23 of the code transmitter CT, impulses of 60 cycle alternating current are supplied to the track rails of section 1T during each "off" period of the coded 100 cycle alternating current, and hence the track relay of section 1T is effectively energized and picked up immediately following the vacating of that section.

The apparatus thus far described is that necessary for a combined wayside and cab signal system in general use except for the circuit network 45 interposed in the 180 code selection circuit and which network is controlled by apparatus embodying my invention. It will be understood, of course, that each signal location of the system is provided with apparatus similar to that 50 described for location A except the apparatus embodying my invention and which latter apparatus would be added at selected points as desired.

As shown in the right-hand end of Fig. 1, the 55 stretch of railway track includes a permanent track hazard at which a relatively low train speed is required for safety. Such track hazard may be, for example, a curve. It is therefore desirable to warn enginemen of trains approaching such track hazard in addition to the usual rules governing speeds over the territory. That 60 a distinctive warning indication of the cab signal may be established as a train enters the section 1T to the rear of the section 2T in which the track hazard exists, I provide additional apparatus that includes four relays TA, TB, TC, and TD. These relays are preferably direct current neutral relays, relays TA, TB, and TC being slow release and slow pickup in character, and 65 relay TD being of the ordinary acting type. The slow release and slow pickup periods of relays TA, TB, and TC may be selected as desired and I shall assume for the purpose of illustrating 70 the operation of the apparatus embodying my 75

invention that the release period of each of the relays is 2 seconds and that the pickup period of each of these relays is 2 seconds. It has been found that direct current relays of this type can be proportioned and adjusted to provide a 2 second pickup period and a 2 second release period when the relay is of the usual construction.

In the drawings certain of the relay contact fingers are shown remote from the winding of the relay for the sake of simplicity. In each such instances the contact finger is given a reference character corresponding to the reference character of the relay plus a distinctive numeral, and each is shown in the position corresponding to the position of the relay.

Relay TA is normally energized over a circuit extending from the B terminal of any convenient source of direct current such as a battery not shown, front contact 24 of relay 2V, wire 25, winding of relay TA and to the C terminal of the same source of current. Relay TA may also be energized over either one of two branch paths one of which includes back contact TC26 and the other of which includes front contact TD27. The energizing circuit for relay TB includes back contact 28 of relay TA, and the energizing circuit of relay TC includes the back contact 29 of relay TB. Relay TD is provided with a pickup circuit including battery terminal B, front contact TA30, back contact TB31, back contact 32 of relay TC, winding of relay TD, and to the C terminal; and it is also provided with a stick circuit including back contact 2V33 as well as its own front contact 34. Thus under normal conditions, that is, when track section 1T is unoccupied and relay 2V is energized, relays TA and TC are picked up and relays TB and TD are released.

The control of the coding means including the code transmitter CT and the associated code selection circuit network is modified by the operation of relays TA, TB, TC, and TD when a train enters section 1T under clear traffic conditions and high train speed is permitted, and a distinctive indication of the cab signal is effected to warn the engineman of the approach to the permanent track hazard. This operation is as follows: As set forth hereinbefore, 100 cycle alternating current of 180 code is ordinarily supplied to the track rails of a section under clear traffic conditions to effect a clear indication of the cab signal. In accordance with my invention, two interruptions of the 180 code current of predetermined fixed intervals are effected, these two intervals being separated by another interval of like duration in which 180 code current is supplied. During the two intervals the 180 code current is interrupted, current of the 120 code is supplied and the approach cab signal indication is established. These two intervals during which 120 code current is supplied and the interval separating these two intervals are each 4 seconds in duration on the assumption that the pickup and release periods of relays TA, TB, and TC are 2 seconds each, since the release period of one relay and the pickup period of a second relay are combined in each case to form an interval. This operation is illustrated in Fig. 3. Looking at Fig. 3, during the first 4 second period subsequent to entry of a train into section 1T under clear traffic conditions, 120 code current is supplied to the track rails of the section, during the second 4 second period 180 code current is supplied, during the third 4 second period 120 code current is supplied, and then this is followed by current of 180 code. Hence,

during the first 4 seconds, an approach cab signal is displayed, during the second 4 seconds a clear cab signal is displayed, during the third 4 seconds the approach cab signal is again displayed, and this is then followed by the display of the clear cab signal as long as the train occupies the section, assuming, of course, that the clear traffic conditions continue to exist.

When the train enters the section 1T and relay 2V is released, the first code circuit selection available can be traced from the secondary winding 9 of transformer TL2 over back contact 35 of relay 2V, wire 36, contact 20, code contact member 120, wire 43, back contact 48 of relay 2V, back contact TB49, back contact TD50, front contact TC51, wire 38, front contacts 39 and 40 of relays 2SA and 2TR, respectively, wires 41 and 13, primary winding 3 of track transformer T1, wire 12, bus bar CX, and wire 42 back to the opposite terminal of secondary winding 9.

Release of relay 2V to open front contact 24 de-energizes relay TA and that relay is released at the end of its release period to close back contact 28 and energize relay TB which relay picks up at the end of its pickup period. When relay TB picks up, the above traced code selection circuit for supplying 120 code current is opened at back contact TB49. With relay TA down and relay TB up, a new code selection circuit is completed and current of 180 code is supplied to the track rails of section 1T. This 180 code selection circuit may be traced from secondary winding 9 over back contact 35, wire 36, contact 22, code contact member 180, wire 37, front contact TE52, back contact TA53, wire 38, and thence as previously traced.

With relay TB picked up and its back contact 29 opened, the relay TC is deenergized and releases at the end of its release period; and with relay TC down and back contact TC26 closed, the relay TA is energized and picks up at the end of its pickup period. Consequently at the end of the next 4 second period, the last traced code selection circuit is opened at the back contact TA53. With relay TC down and relay TA up, a new code selection circuit is formed which extends from primary winding 9 over the elements 35, 36, 20, 120, 43 and 48, back contact TC54, front contact TA53, wire 38, and thence as previously traced, and 120 code current is supplied to the section 1T.

With relay TA picked up, the relay TB is deenergized and releases at the expiration of its release period closing back contact 29 and energizing the relay TC which picks up at the end of its pickup period. During the interval relay TB is down and relay TC has not yet picked up, the relay TD is energized over its pickup circuit which includes front contact TA30, back contact TB31, and the back contact 32 of relay TC. Relay TD once picked up is then retained energized over its stick circuit including back contact 2V33. Thus at the end of the third 4 second period, the last traced code selection circuit for supplying 120 code current is opened at the back contact TC54 and a new code selection circuit is completed for supplying current of 180 code. This connection extends from primary winding 9 over the elements 35, 36, 22 and 180 to wire 37, and thence over front contact TD50, front contact TC51, wire 38 and as previously traced, and this circuit is retained closed until the train vacates the section 1T and the relay 2V is reenergized. Further operation of the relays TA, TB, and TC is prevented since the relay TA is retained energized over front contact TD27 which latter relay is held energized over its stick circuit.

When the train vacates section 1T and 75

relay 2V is picked up, the relay TD is deenergized and at once releases to assume its normal deenergized position. It is to be noted that in the event approach or slow traffic conditions exist in advance of section 1T and relay 2SA is deenergized, or both relays 2TR and 2SA are deenergized, the relays TA, TB, and TC are ineffective to control the code selection connection.

In Fig. 2, the apparatus for the combined way-side and cab signal system is the same as in Fig. 1 and it is thought to be unnecessary to repeat its description. The relays TA, TB, TC, and TD are also the same as in Fig. 1. A direct current relay TF of the ordinary acting type is added and the code selection circuit is carried over contacts of this relay TF. It has been found that ordinary acting relays are more satisfactory than slow acting relays for opening and closing the inductive loads involved in coded track circuits. When a train enters section 1T of Fig. 2 and causes relay 2V to be released, the first code selection circuit includes secondary winding 9, back contact 35 of relay 2V, wire 36, code contact member 120, wire 43, back contact 55 of relay TF, wire 38, front contacts 39 and 40 of relays 2SA and 2TR, respectively, wires 41 and 13, primary winding 3, wire 12, bus bar CX, and wire 42 to the secondary winding 9. In the first 4 second period, subsequent to the release of relay 2V, relay TA is released and relay TB is picked up in the manner described in Fig. 1. With relay TA down and relay TB up, the relay TF is picked up over a circuit including front contact TB56 and back contact TA57. Thus at the end of the first 4 second period, relay TF picks up and opens the first code selection circuit at back contact 55 and closes a new code selection circuit at front contact 58 over which current of the 180 code is supplied as will readily be understood by an inspection of Fig. 2.

At the end of the second 4 second period, relay TC is released and relay TA is picked up. Relay TA on picking up opens the circuit for relay TF at back contact TA57 and relay TF is at once released to switch the code selection circuit back to the circuit for supplying the 120 code current. During the third 4 second period, relay TB is released and relay TC is again picked up, relay TD being also picked up during this period and then retained energized over its stick circuit in the manner described in Fig. 1. Relay TF is now energized over front contact TC59 and front contact TD60 and the code selection circuit is switched back to the 180 code circuit. Since relay TD is retained energized over its stick circuit until the relay 2V is reenergized, further operation of the relays TA, TB, and TC is prevented and current of the 180 code is supplied to the section 1T as long as the train occupies that section. It is clear, therefore, that the apparatus of Fig. 2 is operative to cause a distinctive warning indication of the cab signal to be displayed subsequent to the train entering the section 1T to warn the engineer of approach to the permanent track hazard encountered in section 2T.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a railway track formed into insulated track sections, coding means operative at times to supply coded current of a first code

to the rails of a section under clear traffic conditions in advance and to supply coded current of a second code to the rails of the section under approach traffic conditions in advance, and means controlled by a train upon entry into the section under clear traffic conditions to modify the operation of the coding means to supply current of the second code to the rails for at least one short definite period before current of the first code is supplied to the rails.

2. In combination, a railway track formed into insulated track sections, coding means operative at times to supply coded current of a first code to the rails of a section under traffic conditions which permit a relatively high train speed and to supply coded current of a second code to the rails of the section under traffic conditions which permit a somewhat lower train speed, and means controlled by a train upon entry into the section under the first mentioned traffic conditions to modify the operation of the coding means to supply current of the second code to the rails for at least one short definite period before current of the first code is supplied to the rails.

3. In combination, a railway track formed into insulated track sections, coding means operative at times to supply coded current of a first code to the rails of a section under clear traffic conditions in advance and to supply coded current of a second code to the rails of the section under approach traffic conditions in advance, and means controlled by a train upon entry into the section under clear traffic conditions to modify the operation of the coding means to supply current of the second code for a first short definite period followed by current of the first code for a second short definite period followed by current of the second code for a third short definite period and this followed by an uninterrupted period of current of the first code.

4. In combination, a railway track formed into insulated track sections, coding means operative at times to supply to the rails of a section current coded at a first code or at a second code according to a first or a second traffic condition in advance of the section, and means controlled by a train upon entry into the section under the first traffic conditions to modify the operation of the coding means and supply current of the second code and first code alternately for at least three short definite periods and then supply current of the first code as long as the train occupies the section and the first traffic conditions continue to exist.

5. In combination, a stretch of railway track including a permanent track hazard formed into insulated track sections, coding means operative at times to supply coded current of a first code to the rails of a section under traffic conditions permitting high speed and to supply coded current of a second code to the rails of the section under traffic conditions requiring a restricted speed, and means associated with the track section in the rear of said track hazard to modify the operation of the coding means when a train enters that section under the high speed traffic conditions to supply current of the second code for at least one short definite period prior to supplying current of the first code.

6. In combination, a stretch of railway track including a permanent track hazard formed into insulated track sections, coding means operative at times to supply coded current of a first code to the rails of a section under traffic conditions permitting high speed and to supply coded current
